CLAIM

The ornamental design for a machining center, as shown and described.

DESCRIPTION

FIG. 1 is a perspective view taken from the front, top and right side of a machining center showing the design;

FIG. 2 is a front elevation of the machining center of FIG. 1;

FIG. 3 is a top plan view of the machining center of FIG. 2;
FIG. 4 is a rear elevation of the machining center of FIG. 2;
FIG. 5 is a right side elevation of the machining center of FIG. 2;

FIG. 6 is a left side elevation of the machining center of FIG. 2; and,

FIG. 7 is a bottom plan view of the machining center of FIG. 2.
